UNITED STATES PATENT OFFICE.

WILLIAM DE CEW, OF BUFFALO, NEW YORK.

CAR-COUPING.

SPECIFICATION forming part of Letters Patent No. 274,180, dated March 20, 1883.

Application filed February 5, 1883. (No model.)

To all whom it may concern:

Be it known that I, WILLIAM DE CEW, of Buffalo, in the county of Erie and State of New York, have invented certain new and useful 5 Improvements on Car-Couplings; and I do hereby declare that the following description of my said invention, taken in connection with the accompanying sheet of drawings, forms a full, clear, and exact specification, which will 10 enable others skilled in the art to which it appertains to make and use the same.

My present invention has general reference to improvements in car-couplings; and it consists essentially in the novel and peculiar combination of parts and details of construction, 15 as hereinafter first fully set forth and described, and then pointed out in the claim.

In the drawings already mentioned, which serve to illustrate my said invention more 20 fully, Figure 1 is a longitudinal sectional elevation of a pair of draw-bars, illustrating my novel coupling device. Fig. 2 is a similar view, showing the draw-heads ready for coupling. Fig. 3 is a plan, part being in section. Fig. 4 is a similar view on a larger scale. Fig. 5 is 25 a sectional elevation of a portion of a draw-head, indicating a modified form of my said invention.

Like parts are designated by corresponding 30 letters of reference in all the figures.

The object of my present invention is to solve the problem of constructing a car-coupling in which an ordinary link can be used, and by means of which connection between two 35 cars can be made without danger to the life and limbs of the brakeman or other person employed to attend to the coupling of railway-cars. I attain this end by the use of a link of peculiar construction, or by the use of an ordinary link in a draw-head of novel design in 40 such manner that the said link is held in an elevated position and guided into the opposite draw-head without compelling the attendant to place his hand in front of the bumper.

45 A designates a similar pair of draw-bars, they being constructed exactly alike, so that in describing one of them such description will also answer for the other. This draw-bar A has an internal recess, B, for the reception of 50 the coupling-link E, said coupling-link being retained in position by means of a coupling-

pin, D. This coupling-pin I prefer to construct of flat iron with a reduced portion, d, so as to leave a shoulder, d', Fig. 5, which shoulder, resting upon the end of the link, keeps the 55 same depressed on account of the weight of the said coupling-pin. On the upper end of the said coupling-pin D, I form a crook, D', serving the purpose of a handle, while in the link E, I provide a bridge or stay, G, near one 60 end, so as to produce in said link an oblong aperture, h, Fig. 3, for the reception of the enlarged portion of said coupling-pin E, thus forming a handle for the link to guide the same into the opposite draw-head from the top of 65 said draw-bar, thus avoiding the necessity of placing the operator's hand in front of the bumper-surface C, where such hand is liable to be crushed if the said operator is the least careless when attending to the coupling of 70 cars. To enable the pin D to sustain the link E in an elevated position, as shown in Fig. 2, I form a bend, H, in said link near the bridge G, so that when the shoulder d' of said pin rests upon the portion of the link within the 75 draw-head the opposite end of said link will be raised in a manner readily apprehended; but instead of said bend in the link E, I may form a rise, I, in the draw-head, as shown in Fig. 5, so that the weight of the pin (with the assistance 80 of the operator, if necessary) is capable of depressing the portion of said link within the draw-head, and thus accomplish the desired result in precisely the same manner as the bent link will produce the same. By constructing 85 the draw-head as described with reference to Fig. 5 I am enabled to use an ordinary straight link, while by bending such a link into the shape shown in Figs. 1 and 2 I can use this link and my improved pin in an ordinary draw- 90 bar.

It will thus be seen that when constructing new car-couplings according to my improved design no additional expense will have to be incurred, while at a trifling cost all old draw-heads, &c., may be readily converted into my improved form without necessitating the removal of the draw-heads, or in any other wise disturbing the parts of a freight, &c., car.

It is perfectly obvious that levers and other 100 mechanical means may be devised to operate my coupling-pin from the sides or the top of

the car, or both, if desired, such mechanism being very simple and inexpensive in construction. In this case I may discard the crook D', if necessary, to enable connection being made with such operating mechanism.

By the application of my improved car-coupling to freight, &c., cars, I derive, among others, the advantage of saving time in coupling, because connection can be made with my improved coupling in less time than any other non-automatic coupling, because the link can be actuated by the crook D' on the coupling-pin D laterally as well as vertically, and thus guided into the opposite draw-head, and thereby time saved that would often be lost by misses in making proper connection. If furthermore gain in space, because when coupling is first made one of the pins engages the links on its narrow portion, but as soon as the cars are coupled and pushed together this pin will drop and engage the link on its widest part, thus shortening each connection for a space corresponding to the difference in width of the said coupling-pin, which is quite an advantage in railway appliances of the class mentioned.

It is perfectly obvious that where cars of

different spur or height are to be coupled together such connection can be made in the usual manner by means of S-links and similar well-known contrivances.

Having thus fully described my invention, I claim as new and desire to secure to me by Letters Patent of the United States—

As an improved article of manufacture, a car-coupling consisting essentially of the draw-head A, having the link-receiving recess B and pin-apertures b, of the link E, having the bridge G and the bent portion H, and the pin D, provided with the reduced portion d, shoulder d', and crook D', the whole being constructed and organized for joint operation, substantially in the manner as and for the object specified.

In testimony that I claim the foregoing as my invention I have hereto set my hand in the presence of three subscribing witnesses.

WILLIAM DE CEW.
